UNITED STATES PATENT OFFICE.

PETER MORESI, OF PATERSON, NEW JERSEY, ASSIGNOR TO DEXTER,
LAMBERT & COMPANY, OF PATERSON, NEW JERSEY, A FIRM.

LOOM-SHUTTLE.

SPECIFICATION forming part of Letters Patent No. 734,189, dated July 21, 1903.

Application filed March 30, 1901. Serial No. 53,573. (No model.)

To all whom it may concern:

Be it known that I, PETER MORESI, a citizen of the United States, and a resident of Paterson, in the county of Passaic and State of New Jersey, have invented a new and useful Loom-Shuttle, of which the following is a specification.

My invention relates to a loom-shuttle, and more particularly to a loom-shuttle arranged to carry several quills for the purpose of feeding a weft of several threads as the weaving progresses.

Considerable annoyance has hitherto been caused by the breaking of one of the threads while the weaving progressed to a greater or lesser extent with the other thread, thereby producing a defect in the fabric. This has happened because of the difficulty on the part of the operator to observe at a glance whether one or both of the threads were intact.

The object of my present invention is to provide a simple and effective means for causing the breakage of a companion thread when for any cause one of the threads of the group being fed is broken, thus calling prompt attention to the fact of the breakage and preventing the weaving of one of the threads independently of its companion thread.

A practical embodiment of my invention is represented in the accompanying drawings, in which—

Figure 1 is a top plan view of a two-quill shuttle, showing the parts in the position which they assume when the shuttle is in operation. Fig. 2 is an enlarged top plan view of the central portion of the shuttle, showing the parts to which my invention particularly relates; and Fig. 3 is a view of the same in side elevation, the side of the shuttle being broken away to show the parts within it.

The shuttle is denoted by *a* and the wound quills by *b* and *c*. These may be of any well-known or approved form in the present instance located within the shuttle with their tips over which the thread is withdrawn arranged toward each other and spaced apart. Within the space between the free ends of the quills *b* and *c* there is fixed a frame, in the present instance comprising a bottom plate *d*, two upright end plates *e* and *f*, a central standard *g*, and rails *h* and *i*, leading

from the central standard *g* near its top to the ends *e* and *f* and fixed in position. From the ends *e* and *f* guide-tubes *j* and *k* project in a slanting direction, as clearly shown in the several figures, the slant being away from the central standard *g*. The central standard *g* has fixed thereto, in the present instance about midway of its height and preferably about the height of the guide-tubes *j* and *k*, two pairs of eyes, the one pair being denoted by *l m* and the other pair by *n o*. These pairs of eyes are located upon opposite sides of the central standard *g*, and the members of each pair are in alignment and spaced apart to receive between them the eyes *p* and *q*, located at the juncture of the arms of L-shaped stops suspended from the rails *h* and *i*. The upright arms of these L-shaped stops are provided with eyes *r* and *s*, through which the rails *h* and *i* pass and by means of which the L-shaped stops are suspended from the rails.

The horizontal arms *t* and *u* of the stops project through openings in the ends *e* and *f* of the frame in position to be slid into engagement with or into the ends of the quills *b* and *c*, as shown in dotted lines, Fig. 3, where the stop for the quill *b* has its position for arresting the withdrawal of the thread from the quill *b* represented in dotted lines.

The normal positions of the stops are indicated in full lines in the several figures, and they are thrown out of their normal positions only when their eyes *r* and *s* are permitted to slide up inclines *v* and *w* on the rails *h* and *i*. This happens only when they are freed from their position between pairs of eyes *l m* and *n o* by the breaking of the thread and takes place at the moment the shuttle is abruptly stopped in its box at the end of its throw, the momentum of the stop being sufficient to carry it from its normal position into its dotted position. (Shown in Fig. 3.)

The thread from the quill *b* is denoted by *x* and that from the quill *c* is denoted by *y*. The thread *x* passes into and through the guide-tube *j*, and from its free end it passes through the eyes *n o* and also through the eye *q* in the stop which co-operates with the quill *c* and thence extends up through the guide-ring *z* and out at the front of the shuttle.

The thread y extends into and through the guide-tube k and from its free end through the eyes l and m and through the eye p in the stop which co-operates with the quill b and thence up through the guide-ring z and passes, together with the thread y , through the front of the shuttle.

When for any cause one of the threads breaks—as, for example, the thread y —it will 10 immediately relieve the stop which coacts with the quill b , carrying the thread x , permitting it to slide freely from between the eyes l and m , and this it will do when the shuttle is brought to a sudden stop at the end of its 15 stroke, the eye r on the upright arm of the stop riding up the incline v into the dotted position shown in Fig. 3, presenting the horizontal arm t of the stop in proximity to or within the end of the quill b , thereby causing 20 the thread x to wind around the arm t as it is withdrawn from the quill b and by so doing bind sufficiently to cause it to break. In the same manner if the thread x should 25 break the stop which co-operates with the quill c would be free to jump forward under its own momentum when the shuttle is suddenly stopped in its flight in the opposite direction, causing the stop to slide into position with its horizontal arm, where it catches the 30 thread y and causes it to break.

The above arrangement thus provides for causing the companion thread to break when for any reason one of the threads breaks, thus calling the operator's attention to the defect 35 and enabling him to correct it before serious damage is done.

What I claim is—

1. A shuttle provided with means for supplying separate threads and means under the 40 control of one of the threads and actuated by the stopping of the shuttle at the end of a pick for causing a companion thread to break when one of the threads breaks.

2. A shuttle provided with means for supplying separate threads and with stops mov-

able toward and away from each of the thread-supplying means, the said stops being under the control of the threads and actuated by the stopping of the shuttle at the end of a pick to cause a companion thread to break 50 when one of the threads breaks.

3. A shuttle provided with independent quills for supplying separate threads, stops movable toward and away from the ends of the quills and thread-guides arranged for 55 placing the said movable stops under the control of the threads from the quills to be held normally away from the quills, the stop corresponding to each quill being under the control of the thread from the companion quill 60 whereby the breaking of the thread from one of the quills will release the stop corresponding to the other quill to cause its thread to break, substantially as set forth.

4. A shuttle provided with independent 65 quills, guides for conducting the threads from the quills to a common outlet from the shuttle, stops suspended intermediate of the ends of the quills in position to slide under their momentum toward the ends of the quills, the 70 said stops being provided with eyes normally located in position to receive the threads therethrough as they extend from the quills to the exterior of the shuttle, the stop corresponding to one of the quills being in position to receive the thread leading from the opposite quill whereby the releasing of one of the stops by the breaking of a thread from one of the quills will permit the stop to assume a position to cause the breaking of a 80 thread on the quill to which it corresponds, substantially as set forth.

In testimony that I claim the foregoing as my invention I have signed my name, in presence of two witnesses, this 27th day of 85 March, 1901.

PETER MORESI.
